CLAIM

[21] Appl. No.: 609,212

The ornamental design for a combined circuit breaker
and current limiting attachment, as shown and de-
scribed.

[22] Filed: Nov. 5, 1990

DESCRIPTION

[52] U.S. Cl. D13/160
[58] Field of Search D13/160; 361/115, 103;
335/202, 132, 17, 205

FIG. 1 is a front and upper right perspective view of a
combined circuit breaker and current limiting attach-
ment showing our new design;

FIG. 2 is a rear and upper left perspective view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a right side elevational view thereof; and,

FIG. 8 is a left side elevational view thereof.
